UNITED STATES PATENT OFFICE.

LESLIE F. PORTER, OF PASSAIC, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed June 25, 1925. Serial No. 39,404.

This invention relates to telephone signaling systems and particularly to improvements in the means for and method of operating long distance toll telephone lines. 5
5 In operating long distance toll telephone lines the method of handling traffic known as the dispatch method of operation is often employed. In systems of this sort calls originating with subscribers, whose lines terminate at a local central office, are usually extended over switching trunks to a so-called dispatch office having access to long distance toll lines terminating at a similar distant dispatch office where the connection is completed through another switching trunk to the local office at which the desired subscriber's line terminates. Systems involving this method of operation have been disclosed as for example, in Patent No. 1,555,002 granted 10
10 September 29, 1925, to E. A. Gray. When the local offices, at which the calling and called subscribers' lines terminate, are so located that long distance toll lines are required as interconnecting links and dispatch offices are involved for establishing of connections it is evident that a number of different signals, various communications between a number of operators and the preparation of a number of tickets for recording 15
15 the connections are involved. For example, at the originating dispatch office the calls coming in over toll switching trunks are first attended to by a so-called report operator who communicates over assignment trunks with a so-called dispatch operator, who in turn communicates with another dispatch operator at the distant dispatch office over a long distance toll line and at which office similar arrangements are made to cause the 20
20 connection to be completed to a wanted subscriber through an assignment trunk, a report operator, a switching trunk and the distant local office. It is with the signaling involved in connections of this sort that this invention is concerned, and in particular with a means for and method of transmitting disconnect signals to a report operator and a dispatch operator at a dispatch office when a calling subscriber hangs up his receiver. 25
25

It is an object therefore of this invention to provide an improved method and means for transmitting the disconnect signals to the said report and dispatch operators in an

efficient manner and so that such signals will not interfere with conditions of the signaling apparatus used in these circuits for setting up the connection, signals controlled by such signaling apparatus being naturally set to indicate to said operators its condition at the time the disconnect signal is given. 30
30

To attain this and other objects of the invention, there is provided in accordance with one feature thereof, a circuit arrangement at the switching trunks and in the report and dispatch operator's cord circuits, whereby a disconnect signal incoming through a switching trunk is effective to operate disconnect signals in the report and dispatch operator's cord circuits simultaneously to indicate that the calling subscriber has hung up his receiver and that therefore these operators may break down the connection by removing their cord circuits therefrom. 35
35

Another feature of the invention resides in the provision of such a circuit arrangement whereby a disconnect signal in the report operator's cord circuit is controlled over the sleeve circuit between the switching trunk and the operator's cord circuit, while the disconnect signal in the dispatch operator's circuit is controlled over either one of the talking conductors of the report operator's cord circuit, the assignment trunk involved and the dispatch operator's cord circuit. 40
40

Another feature of the invention resides in means whereby either alternating or direct current sources may be employed for supplying the signaling current over either one of the talking conductors to control the disconnect signal in a dispatch operator's cord circuit. 45
45

The invention is illustrated in the accompanying drawings in which Fig. 1 shows a calling subscriber's line, a local automatic office diagrammatically represented, a switching trunk circuit leading from said local office and a report operator's cord at a dispatch office; Fig. 2 shows an assignment trunk circuit and dispatch operator's cord at said dispatch office and a long distance toll line terminating thereat, while Fig. 3 illustrates the use of alternating current for operation of the disconnect signal at the dispatch operator's position. 50
50

In order to more fully appreciate the significance of the dispatch method of operation in handling traffic and in particular

2

to make clear the relation of this invention to the signaling between operators and subscribers involved in a connection established on this basis, a short description of the method employed in modern offices will be made followed by a more detailed description of the signaling taking place at the dispatch office during the setting up and release of such a connection. Referring now to 5 the drawing but more generally relying on the description of the dispatch method itself, if it is assumed that a long distance connection is desired between a subscriber at the local office through a dispatch office over 10 a long distance toll line through another dispatch office to a subscriber at a local office, the operation will be as follows: The local operator, usually a recording operator, would 15 pass detailed information relating to a call by means of a ticket to the dispatch operator at the dispatch position. The dispatch operator in turn, passes the detailed information thereon to a dispatch operator at a distant office over a non-busy long distance toll line. The distant dispatch operator records 20 this information on a ticket, assigns a number thereto, which number she passes on to the dispatch operator at the originating end of the toll line where this dispatch operator 25 records the number on her ticket of the call. The distant dispatch operator now assigns this call to an assignment trunk leading to a report operator's position and both dispatch operators note the number of this assignment trunk on their respective tickets. The report operator takes the ticket from the dispatch table at the originating dispatch office and connects one of her cord circuits to a switching trunk leading to the 30 local office for the ordering up of the calling subscriber, which may be done either by dialing the subscriber or by the manual method. The calling subscriber, however, is not rung at this time but is held under the control of the report operator. The report operator now connects the other end of the cord circuit used with an assignment trunk leading to the dispatch operator and a lamp is lighted at this position to indicate that the 35 subscriber is ready for the connection. Simultaneously with these operations similar operations are taking place at the distant dispatch office, that is, the report operator at this office connects a cord to a switching trunk and orders up the called subscriber and advises him to hang up his receiver as she will call him again for a long distance connection when it is ready. When the report operator at the distant office is connected with the assignment trunk, a lamp at the 40 dispatch operator's position at this office is lighted, so that this dispatch operator can now inform the dispatch operator at the originating office that the called subscriber has 45 been secured and is ready to receive the call.

The dispatch operator at the originating office on receiving this information assigns a long distance toll line for the completion of this connection, and the dispatch operator at the originating office now connects this long 50 distance toll line through the assignment trunk and the report operator's cord that were used for the connection to the calling subscriber and rings the calling subscriber. The report operator associated with this 55 dispatch operator at this time receives a signal which is interpreted as an indication that the long distance toll line has been assigned and when the calling subscriber answers, the report operator informs the calling subscriber that a connection is ready for completion. At the same time the report operator informs the dispatch operator that the call has been answered. Similar operations take place simultaneously at the distant dispatch office and when the dispatch operator at the distant office is ready, she 60 will so inform the dispatch operator at the originating office and when the dispatch operator at the originating office is ready she will also inform the dispatch operator at the distant office to go ahead. The dispatch operator at the originating office now signals the report operator that the distant office 65 is ready and the connection is extended to the report operator. The report operator will now associate her telephone set with the assignment trunk which is now connected directly to the called subscriber. Similar 70 operations are taking place at the distant office except that the report operator at this office has actually connected the calling subscriber through to the long distance toll line so that the report operator at the originating exchange will now communicate with the called subscriber to make sure that the connection has actually been established and will then by the operation of keys in her cord circuit, join the calling and called subscriber together. Conversation between the 75 subscribers may now take place and when the conversation ceases and the calling subscriber hangs up his receiver a simultaneous disconnect signal is received by the report operator and the dispatch operator and the connection may be taken down.

To secure a more accurate understanding of a connection of this type in regard to the actual signaling functions taking place, a detailed description will now be made of the operations taking place at the dispatch office in extending a call through the switching trunk, the report operator's cord circuit, the assignment trunk and the dispatch operator's cord to the long distance toll line 80 as illustrated on the drawings.

From the above general description of the setting up of a connection it will be seen that the first action on the part of the operator at a dispatch office in actually establishing 85

a physical connection is for the report operator to connect with a switching trunk to order up the calling subscriber's line, although the calling subscriber is not rung at this time but held under control of the report operator. Therefore, when plug 1 of the report operator's cord is inserted in jack 2 of the switching trunk, relay 3 is operated over the following circuit. Battery, 10 lamp 5, sleeve contacts of plug 1 and jack 2, winding of relay 3 to ground. Lamp 5 does not operate at this time as the resistance of the sleeve circuit through the winding of relay 3 is too high to permit sufficient current 15 to flow for the operation of the lamp. As the report operator's cord circuit may be of any well-known type equipped with facilities for dialing subscribers' lines connected to the cord, it has not been illustrated in detail. It is sufficient to note that when the report operator's cord circuit has functioned to prepare and connect the common dialing equipment thereto, a source of battery will be connected to the tip conductor of the cord 20 and current from this source causes the operation of relay 10 in the switching trunk through the upper armature and back contact of relay 10 and the winding of relay 10 to ground. Relay 10 in operating provides a locking circuit for itself independent of current on the tip conductor, which circuit may be traced from battery at the armature and front contact of relay 3. The operation of relay 10 completes the tip and 25 ring conductors of the switching trunk to the dialing equipment in the report operator's cord in one direction and through the automatic switching equipment connected to this switching trunk at the local office. The 30 transmission of dialing impulses to select the calling subscriber's line may now be begun by the report operator. It should be understood that automatic selection of a subscriber may be done by means of any 35 automatic equipment well-known in the automatic switching art. When the calling subscriber's line has been seized, the battery supply on the tip and ring conductors of the switching trunk is reversed according to the well-known practice as shown in 40 Patent No. 1,553,837 granted to R. L. Stokely, September 15, 1925, and the polarized relay 11 is operated. The circuit of relay 11 may be traced from the ring conductor at the lower left-hand connection to 45 repeating coil 15 through polarized relay 11, back contact of the inner upper armature of relay 12, front contact of the inner lower armature of relay 10, ring contacts of jack 50 2 and plug 1, thence through the dial (not shown) in the report operator's cord, tip contacts of plug 1 and jack 2, upper armature and front contact of relay 10, and the 55 lower armature and normal contact of relay 12 to the tip conductor of the switching 60 trunk. The broken lines in the tip and ring conductors of the report operator's cord leading to plug 1 indicate, among other things, a key by means of which a dial is bridged across these conductors in the manner shown in Patent No. 1,448,576 granted March 13, 1923, to W. B. Strickler. The operation of relay 11 causes the operation of relay 12 over an obvious circuit and relay 12 is locked up to battery at the lower 70 outer armature and front contact of relay 10. Relay 12 in operating opens the circuit for relay 11 and instead inserts the repeating coil 15 between the inward and outward ends of the switching trunk to insulate the 75 switching trunk from direct current signaling battery. Relay 12 also connects relay 13 across the outgoing tip and ring of the switching trunk for translation of the supervisory signals from this end through the switching trunk to the dispatch operator's 80 position.

As previously stated the calling subscriber is not called at this time but is held by the report operator until wanted in the connection as will be hereinafter described. As an indication to the report operator that the calling subscriber's line is thus held, lamp 5 will now be lighted as the signaling battery across the tip and ring conductors of 85 the switching trunk will operate relay 13. The operation of relay 13 supplies at its upper inner armature and front contact a path to ground, through the low resistance 90 14 for the sleeve circuit and lamp 5 so that 95 this lamp will now light while relay 3 is 100 still maintained operated.

The next action toward establishing a connection will be that the report operator inserts plug 50 into jack 100 of the assignment 105 trunk. A circuit will then be closed as follows: battery, lamp 51, sleeve contacts of plug 50 and jack 100, winding of relay 101 to ground. This circuit causes the operation of relay 101, but lamp 51 is not lighted as the resistance through the winding of 110 relay 101 is too high. The operation of relay 101 closes an energizing circuit for relay 102. Relay 102 in operating closes a circuit 115 for the so-called OK lamps 103 at the dispatch operator's position and multiple positions thereof and the lighting of these lamps indicates to this particular dispatch operator that the calling subscriber is ready 120 to be connected up for a long distance connection and to other dispatch operators that this assignment trunk is engaged. This relay also opens at its lower outer armature and back contact a circuit for relay 105, 125 which relay is used in certain disconnect supervisory functions as will hereinafter be described.

As previously stated similar operations 130 take place at the distant dispatch office and when the dispatch operator at this office

receives the information that the called subscriber has been secured and is ready to receive the call, this dispatch operator assigns a long distance toll line such as 400 for use in completing the connection between these two subscribers. It should be explained at this point that the dispatch operator is provided with a number of cords connected through to long distance toll lines, that is, 5 plugs such as 350 are connected through at report operator's positions to jacks such as 351 of long distance toll lines, such as 400. The next action therefore on the part of the dispatch operator towards employing 10 this particular long distance toll line in the connection will be to insert plug 300 of her cord into jack 110 of the engaged assignment trunk and a circuit will then be completed as follows: battery, lamp 302, lower 15 outer contacts of ringing key 303, sleeve contacts of plug 300 and jack 110, winding of relay 111 to ground. This circuit causes the operation of relay 111 but as the resistance through the winding of this relay is 20 high lamp 302 is not operated at this time. The operation of relay 111 closes an energizing circuit for relay 112 and this relay in turn provides a locking circuit for itself to ground at the upper inner armature and 25 front contact of relay 102. The operation of this relay opens the circuit for the OK lamps 103 at the upper inner armature and back contact so that these lamps are extinguished. This relay also closes a circuit 30 for the so-called guard lamp 115 associated with the jack 100 at the report operator's position and this lamp in lighting informs the report operator that a long distance toll line has been assigned for the establishing 35 of this connection.

The next action required is that the dispatch operator rings the calling subscriber and to this end she operates her splitting key 306 towards the right to keep the long 40 distance toll line disconnected from the assignment trunk during ringing and she also operates the ringing key 303 towards the left to apply ringing current over the tip conductors to ring the calling subscriber's line. This ringing current is applied over 45 the following circuit: battery, upper outer right-hand closed contacts of splitting key 306, upper left-hand closed contacts of ringing key 303, tip conductor of the dispatch operator's cord, tip terminals of plug 300 and jack 110, tip conductor of the assignment trunk, tip terminals of jack 100, plug 50, tip conductor of the report operator's cord, tip terminals of plug 1 and jack 2, upper armature and front contact of relay 55 10, lower armature and front contact of relay 12, upper right-hand winding of repeating coil 15, winding of relay 16 to ground. This causes the operation of relay 60 16 which now applies ringing current at its

armatures and front contacts to the calling subscriber's line. It should be noted that the lamp 5 at the report operator's cord is lighted before the ringing current is applied to the switching trunk and is extinguished when relay 16 operates, as relay 13 will then be released, but as soon as the ringing current is removed and relay 16 released, if the calling subscriber does not answer, lamp 5 will again be lighted. However, as soon as 70 the calling subscriber answers the signaling battery on the switching trunk will be removed and relay 13 released, so that lamp 5 will then be extinguished and the report operator thereby informed that the calling subscriber has answered and the report operator now in the usual manner by associating her telephone set with her cord informs the calling subscriber that the long distance connection is about to be completed. 75

The calling subscriber will therefore remain on the line and the report operator also at this time informs the dispatch operator that the calling subscriber has answered. To this end the report operator operates her ringing key 53 in the manner well known in the art to apply ringing current on the tip conductor of the cord, the assignment trunk and the dispatch operator's cord to cause the 80 operation of relay 315. The circuit for the operation of this relay is as follows: battery, contacts 54 of ringing key 53, tip terminals of plug 50 and jack 100, tip conductor of the assignment trunk, tip terminals of jack 110 and plug 300, upper normal left-hand contacts of ringing key 303, upper winding of retardation coil 316, lower winding of relay 315 to ground. Relay 315 provides a locking circuit for itself from battery through its upper winding and lower armature and front contact to ground at the splitting key 306, which is still in operated condition. Relay 315 in operating also closes a circuit for the so called "ready with" lamp 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760

While these operations are taking place at this dispatch office, similar operations have taken place at the distant dispatch office and when the two dispatch operators have been informed each by the other that the calling and called subscribers are ready to be connected over the long distance toll line, the dispatch operator at this office signals the report operator that the connection may be completed. The operations at this time will be as follows: The dispatch operator operates her ringing key 303 to the left so that the lower contacts of this ringing key open the sleeve circuit to the assignment trunk

and relay 111 is thereby released. The release of relay 111 closes a circuit for relay 118, from battery at lamp 51 over the corresponding sleeve circuit and the lower outer 5 armature and front contact of relay 112 to ground so that this relay now locks up in parallel with relay 101. The lamp 51 in the report operator's cord now lights as the resistance through the winding of relay 118 is 10 low as compared with the resistance through the winding of relay 101 and the report operator is thereby informed that the connection is ready to be completed. The dispatch operator then restores her splitting key 306 15 to normal and the connection is thereby completed to the report operator, while the report operator connects her telephone set to the assignment trunk through the dispatch operator's cord circuit over the long distance 20 toll line and as similar operations are simultaneously taking place at the distant dispatch office except that the report operator at this office has now connected the calling subscriber through to the long distance toll 25 line, the report operator at this office will be in communication with the called subscriber. The report operator after making sure that the called line is actually connected restores her talking key not shown and the 30 splitting key 52 so that the calling and called subscriber will now be connected and conversation may begin.

When the subscribers have finished their conversation and the calling subscriber hangs up his receiver, battery is again supplied at 35 the switching trunk to operate relay 13 which now reduces the resistance of the sleeve circuit to the report operator's cord by connecting the sleeve circuit to ground through the resistance 14, at the upper lower armature and front contact. This relay also 40 simultaneously connects battery through a resistance 17 to the ring conductor of the connection at its upper outer armature and front 45 contact. The effect of these connections to ground and battery is that the report operator and dispatch operator are simultaneously signaled to indicate that the calling subscriber has hung up his receiver and that 50 the connection may therefore be taken down.

The reduction in resistance of the sleeve circuit causes lamp 5 to be lighted while the circuit from battery through resistance 17 over the ring conductors of the connection may be 55 traced as follows: battery, resistance 17, upper outer armature and front contact of relay 13, lower right-hand winding of repeating coil 15, upper inner armature and front contact of relay 12, lower inner armature and front contact of relay 10, ring terminals of jack 2 and plug 1, ring conductor of the report operator's cord, terminals of plug 50 and jack 100, ring conductor of the assignment trunk, ring terminals of jack 60 110, plug 300, lower inner closed contacts of

ringing key 303, lower winding of retardation coil 316, winding of relay 320 to ground. This causes the operation of relay 320 which causes lamp 302 to be lighted over an obvious circuit. Thus lamps 5 and 302 are simultaneously lighted, by the calling subscriber hanging up his receiver, so that the report operator and the dispatch operator, respectively, are simultaneously informed that the connection may be taken down. 75

If now the report operator removes plug 1 from jack 2, the relays in the switching trunk will be restored to normal position and signals 5 and 302 will be extinguished.

When the report operator removes plug 50 from jack 100, relays 101 and 102 in the assignment trunk circuit will be restored and a circuit for relay 105 completed as follows:

battery, upper outer armature and front contact of relay 112, lower outer armature and back contact of relay 102, winding of relay 105, interrupter 120 to ground. Interrupter 120 will thus cause the alternate operation and release of relay 105 which actions on the pair of relay 105 will alternately close 85 and open a circuit through low resistance 121, for the sleeve circuit to lamp 302, causing this lamp to alternately be lighted and extinguished. This circuit may be traced as follows: battery, lamp 302, lower closed contacts of ringing key 303, sleeve terminals of plug 300 and jack 110, low resistance 121, upper outer armature and back contact of relay 102, armature and back contact of relay 105. 90

This alternate lighting and extinguishing of lamp 302 is taken thus as an indication by the dispatch operator that the report operator has restored her portion of the connection and the dispatch operator now therefore removes plug 300 from jack 110. 95 Lamp 302 is thereby extinguished and the relays 111 and 112 in the assignment trunk are restored to normal.

It is evident that the condition of these circuits is such that the operation of the signal 100 302 from battery applied to the ring conductor of the connecting circuits by the operation of relay 13 may also be accomplished by the applying of battery to the tip conductor instead of the ring conductor, thus allowing considerable flexibility in the choice of types of interconnecting cords and trunk circuits without having to make any material changes in the application of this phase of the invention. To further emphasize the 110 flexibility of the invention, it should be pointed out that in place of the direct current supply for operating the ringing relay 302, an alternating current supply may be 120 used. Fig. 3 illustrates how this can be accomplished, that is, an alternating current source 17' may be connected to the front contact associated with the upper outer armature of relay 13 and in place of relay 320, an 125 alternating current responsive relay 320', 130

may be substituted, so that this relay will respond upon the operation of relay 13 and cause the energization of lamp 302.

What is claimed is:

5. 1. In a telephone system, subscribers' lines, means at a dispatch office for extending a connection from a subscriber's line through said dispatch office including a switching trunk incoming from the subscriber's line, a 10 report operator's cord, an assignment trunk and a dispatch operator's cord connected in series, means for simultaneously signaling at the report operator's cord over the sleeve conductors of the switching trunk and the 15 report operator's cord and at the dispatch operator's cord over the ring conductors of the switching trunk, the report operator's cord, the assignment trunk and the dispatch operator's cord comprising sources of current 20 and means responsive to the act of the subscriber in replacing his receiver for applying currents from said source to said switching trunk.
2. In a telephone system, subscribers' lines, means at a dispatch office for extending a connection from a subscriber's line through said dispatch office including a switching trunk incoming from the subscriber's line, a report operator's cord, an assignment trunk and a dispatch operator's cord connected in series, means for simultaneously 25 signaling at the report operator's cord over the sleeve conductors of the switching trunk and the report operator's cord and at the dispatch operator's cord over one of the talking conductors of the switching trunk, the report operator's cord, the assignment trunk and the dispatch operator's cord comprising sources of current and means responsive to 30 the act of the subscriber in replacing his receiver for applying currents from said sources to said switching trunk.
3. In a telephone system, subscribers' lines, means at a dispatch office for extending a 35 connection from a subscriber's line through said dispatch office including a switching trunk incoming from the subscriber's line, a report operator's cord, an assignment trunk and a dispatch operator's cord connected in series, means for simultaneously signaling at the said report operator's cord with direct 40 current signals over the sleeve conductors of the switching trunk and the report operator's cord and at the dispatch operator's cord with currents of different character over one 45 of the talking conductors of the switching trunk, the report operator's cord, the assignment trunk and the dispatch operator's cord said currents being applied to said circuits in 50 response to means for supplying energy to the said switching trunk responsive to the act of the subscriber in replacing his receiver on its hook.
4. In a telephone system, subscribers' lines, 55 long distance toll lines, means for extending a connection from a subscriber's line to a long distance toll line through a dispatch office including a switching trunk incoming from the subscriber's line, a report operator's cord, an assignment trunk, a dispatch operator's cord and a long distance toll line connected in series, means for signaling at the report operator's cord responsive to energy incoming over the switching trunk when a subscriber's line is seized, means for signaling at the incoming end of the assignment trunk responsive to the connection of the report operator's cord to said assignment trunk, means for discontinuing said signaling at the incoming end of the assignment 60 trunk in response to the connection of a dispatch operator's cord to said assignment trunk, means for signaling at the outgoing end of the assignment trunk responsive to the connection of said dispatch operator's cord to said assignment trunk, means at the dispatch operator's cord for transmitting ringing signals to the switching trunk, means at a switching trunk responsive to said ringing signals for transmitting ringing signals over the switching trunk to the connected subscriber's line, means at the switching trunk responsive to the removal of energy by said subscriber's line at said switching trunk for discontinuing the signaling at the report operator's cord, means at the report operator's cord for signaling at the dispatch operator's cord, means at the dispatch operator's cord for signaling at the report operator's cord, and means for signaling at the report operator's cord and the dispatch operator's cord simultaneously in response to the act of the subscriber in replacing his receiver on its hook.
5. In a telephone system, subscribers' lines, long distance toll lines, means for extending a connection from a subscriber's line to a long distance toll line through a dispatch office including a switching trunk incoming from the subscriber's line, a report operator's cord, an assignment trunk, a dispatch operator's cord and a long distance toll line connected in series, means for signaling at the report operator's cord responsive to energy incoming over the switching trunk when a subscriber's line is seized, means for signaling at the incoming end of the assignment trunk responsive to the connection of the report operator's cord to said assignment trunk, means for discontinuing said signaling at the incoming end of the assignment trunk in response to the connection of the dispatch operator's cord to said assignment trunk, means for signaling at the outgoing end of the assignment trunk responsive to the connection of the dispatch operator's cord to said assignment trunk, means at the dispatch operator's cord for transmitting ringing signals to the switching trunk, means at a switching trunk responsive to said ringing signals for transmitting ringing signals over the switching trunk to the connected subscriber's line, means at the switching trunk responsive to the removal of energy by said subscriber's line at said switching trunk for discontinuing the signaling at the report operator's cord, means at the report operator's cord for signaling at the dispatch operator's cord, means at the dispatch operator's cord for signaling at the report operator's cord, and means for signaling at the report operator's cord and the dispatch operator's cord simultaneously in response to the act of the subscriber in replacing his receiver on its hook.

ing signals for transmitting ringing signals over the switching trunk to the connected subscriber's line, means at the switching trunk responsive to the removal of energy by 5 said subscriber's line at said switching trunk for discontinuing the signaling at the report operator's cord, means at the report operator's cord for signaling at the dispatch operator's cord, means at the dispatch operator's cord for signaling at the report operator's cord, means for signaling at the report operator's cord and the dispatch operator's cord simultaneously in response to energy incoming over the switching trunk when the 10 subscriber connected thereto hangs up his 15

receiver, means for discontinuing the signaling at the report operator's cord in response to disconnection by the report operator of her cord from the assignment trunk, means for signaling at the dispatch operator's cord responsive to the disconnection of the report operator's cord from the assignment trunk, and means for discontinuing the signaling at the dispatch operator's cord in response to the disconnection of the dispatch operator's 20 cord from the assignment trunk. 25

In witness whereof, I hereunto subscribe my name this 23 day of June A. D., 1925.

LESLIE F. PORTER.
